United States Patent Office

Des. 193,828
Patented Oct. 9, 1962

193,828

CHAIN SAW

Sam Burns, Louisville, Ga., assignor to Whitehead Chain
Saw Company, Atlanta, Ga., a corporation of Georgia

Filed Apr. 26, 1961, Ser. No. 64,919

Term of patent 14 years

(Cl. D93—3)

FIG. 1

FIG. 2

FIG. 3 is a top plan, and

FIG. 4 is a front elevation.

The dominant features of my design reside in the portions shown in full lines.

I claim:

The ornamental design for a chain saw, as shown and described.
